UNITED STATES PATENT OFFICE

JOHN F. PETERS, OF ROCHESTER, NEW YORK, ASSIGNOR TO AMERICAN CAN COMPANY, OF NEW YORK, N. Y., A CORPORATION OF NEW JERSEY

COLLAR AND CAN ASSEMBLING MACHINE

Application filed October 4, 1928, Serial No. 666,468. Renewed February 19, 1931.

The machine provided by the present invention has for its purpose the assembly of separate collar members within can bodies to produce a construction in which a side tearing strip may be employed to open the container and the portion of the can removed by tearing away said strip may be employed as a temporary closure.

For a better understanding of the invention, reference may be had to the co-pending application of John M. Young, Serial No. 514,588, which is assigned to the assignee of the present invention, by whom containers of this general form have been widely manufactured since the invention of said application was made.

An important object of the invention is the provision of an efficient and rapidly operating machine for the purpose referred to above, which is wholly automatic in action and which performs the assembling operation without the necessity of manual handling by attendants of the parts to be assembled.

Another object of the invention is the provision of means whereby the machine may be adapted for operating upon cans of different height.

It is also an object of my invention to provide a can body and collar assembling machine which involves a minimum number of operating parts and which will be unlikely to require frequent stoppage for attention or repair.

Another object is the provision of a machine of this character which is continuous in operation and in which the can bodies are rounded up, or trued, and the collars inserted therein while the feeding devices continue to move said parts through the machine, with consequent high speed of operation.

Numerous other objects and advantages of the invention will be apparent as it is better understood from the following description, which, taken in connection with the accompanying drawings, discloses a preferred embodiment thereof.

Referring to the drawings,

Figure 1 is a side elevation of the machine, certain parts being shown in section for the sake of better illustration;

Fig. 2 is a plan view, partially broken away to disclose certain features of construction;

Fig. 3 is a detail view of the adjusting yoke whereby the machine is adapted to operate upon cans of different height, said view being 55 taken substantially on the section line 3-3 in Fig. 2;

Fig. 4 is a section taken substantially on the line 4-4 in Fig. 1; and

Fig. 5 is a section taken substantially on the 60 line 5-5 of Fig. 1.

The machine is supported upon a frame, comprising a bed 21, legs 22 and 23 and upward extensions 24 and 25, a top plate 26 being secured at its opposite ends to upper extremities of said extensions. Said plate is widened at the center and is provided with an opening 27 through which the can bodies and collar members, indicated, respectively, by the reference characters 28 and 29, are adapted to be fed. A body chute is formed by means of retaining plates 31 and 32 and inwardly extending guides 33 and 34, said chute extending from a suitable point of delivery through the plate 26 and being adapted to direct the can bodies into the pockets of spaced turret members 35 and 36. The retaining plate 31 is held in place by means of an adjusting block 37, which is held to the top plate 26 by means of screws 38 and is secured to said retaining plate 31 by means of screws 39. The guides 33 and 34 are secured to the retaining plates 31 and 32 by means of cap screws 41.

A delivery chute for the collar members is 65 provided adjacent the can body chute and is formed by the retaining plate 32, a retaining plate 42 and guide 43. An adjusting block 44, corresponding to the block 37, is employed to hold the retaining member 42 70 in desired position.

A turret 45 is provided adjacent the turret member 36 and is adapted to receive and rotate the collar bands 29 in axial alignment with the can bodies 28. Said turret members 35 and 36 and the turret 45 are mounted on a main shaft 46, which has bearings 47 and 48 in the uprights 24 and 25 at the opposite ends of the machine. The can bodies 28 and collar bands 29 having been delivered into 75

their respective feeding chutes, fall by gravity into the turrets just described, being received at a station A at which they are arranged in axial alignment. The shaft 46 is continuously rotated by means of a large gear 49, mounted on one end thereof and meshing with a pinion 51 on a short shaft 52, which latter has a bearing 53 depending from the under side of the frame bed 21 and a bearing 54 integral with the end of said bed, said shaft being driven from any suitable source of power by a belt taking over a pulley 55 carried on the outer end thereof. Rotation of the turrets, in counter-clockwise direction, 10 brings the can bodies and collar members to a station indicated in Figs. 4 and 5 by the reference character B and at this point, the can body is rounded up, or trued, by means of a turret 56 having pockets 57 cooperating 15 with pockets 58 of the turret member 36 to bring the upper part of the can body to true circular form prior to the insertion of the collar member 29 therein. The collar is also accurately shaped by the turret 56 cooperating 20 with the collar turret 45, it being noted that said first-mentioned turret is of such width as to engage both the can body and collar and is of slightly different diameter at its opposite ends for this purpose. Said turret 25 56 is mounted upon an auxiliary shaft 59, which is journaled in a bearing 61 formed in a bracket 62 extending laterally from the bed 21, and a bearing 63 formed in a bracket 64 projecting from the upright 25. Said shaft is thus held in parallel relationship with respect to the shaft 46 and carries, on its outer 30 end, a gear 65 which meshes with a gear 66 on said shaft 46, the turret 56 being thus rotated in timed relationship with the turret members 35 and 36.

A can body and collar member having arrived at the station B, they are assembled by mechanism to be now described. Chucks 67, corresponding in number to the pockets 45 of the turret members 35 and 36 and the turret 45, are carried on sliding shafts 68 having bearings in a carrier member 69 keyed to the main shaft 46. Each chuck 67 is formed with a tapered outer face 71 and 50 an annular shoulder 72, being thus adapted to enter within a collar band 29 and to move the same inwardly to a predetermined position within a can body 28. The chuck is reciprocated in desired timed relationship to the 55 rotation of the turrets by means of a cam 73, bolted at 74 to the upright 25 and being provided with a cam groove 75 operating upon a cam following roller 76, which is mounted upon a stud 77, secured in a yoke 78 60 formed at the rear end of the shaft 68. By this construction, it will be obvious that the chucks 67 are reciprocated periodically as they are rotated in axial alignment with the can body and collar turrets upon the shaft 46. 65 In this manner, the collars are inserted, this

action taking place just after the body has been rounded up at the station B and during the time that it is moving between said station B and a station C, indicated in Figs. 4 and 5. It will be noted that the retaining plate 32 extends downwardly between the can body and collar at the station A, as indicated in Figs. 1 and 5, but is cut away beyond the station A, so that when the parts arrive at the station B, the collar may be inserted. 70

A feature of my invention is the outward flanging of the end of the can body at which the collar is to be inserted, as indicated in Fig. 1. This flanging is utilized to facilitate the ready and accurate insertion of the collar, and thereafter does or may constitute a double seaming flange when the can is closed in the usual manner of closing sanitary cans. The flanging of the can body may be produced before the cans are fed into the collar-inserting machine, or may be produced at any convenient time. 75

Adjacent the turret member 35, I provide a large disk 79, which is formed with a hub 81 slidably mounted upon the shaft 46 by means of a feathered connection clearly illustrated in Fig. 1. Said disk is of sufficient diameter to engage the bottoms of all of the cans in the turret members 35 and 36 and holds said cans against endwise movement as the collar bands are being inserted. At the end of the hub 81, there is provided a recessed collar 82, shown in detail in Fig. 3. A yoke 83, secured to an adjusting bar 84, fits into the recessed collar 82, said adjusting bar 84 being formed with a slot 85 through which extend studs 86 by which the bar is clamped to an extension 87 of the turret 24. By means of this slotted connection, the disk 79 may be moved along the shaft 46 to vary the distance between it and the chucks 67 to accommodate cans of different height. 90

The forward stroke of the chuck 67 is completed and the chuck is withdrawn before the can body reaches the station C, it being understood that the length of the stroke is governed by the formation of the cam groove 75 and is calculated to arrange the collar at such position within the can body that it will be opposite a tearing strip set off by score lines in the latter, which preferably are located a short distance below the top. The chuck having been withdrawn, the assembled cans are discharged from the machine through an inclined run-way 88 mounted upon a bracket 89 supported from the bed 21. A horizontal bar 91 is secured to a yoke 92 extending upwardly from said bed 21 and is turned upwardly at its inner end, as indicated at 93. Said bar is adapted to contact with the cans to remove them from the turret pockets at the discharging station C. 100

It is thought that the invention and many of its attendant advantages will be understood from the foregoing description, and it 105

will be apparent that various changes may be made in the form, construction and arrangement of the parts without departing from the spirit and scope of the invention, or sacrificing all of its material advantages, the form hereinbefore described being merely a preferred embodiment thereof.

I claim:

1. In a machine for making cans of the character described, the combination of means for arranging a can body and collar member in axial alignment, and means having a diameter equal to the interior diameter of the can body and adapted to propel the collar and having a portion of smaller diameter to enter within the collar, said smaller portion entering within and truing said collar member for automatically inserting said member within an open end of said can body. 70
2. In a machine for making cans of the character described, the combination of means having pockets for arranging a can body and collar member in axial alignment, chutes for feeding can bodies and collar members into said pockets, said chutes having a plate separating the collar members from the bodies when they are deposited in the pockets, and reciprocating means entering within and truing said collar member for automatically internally truing and inserting said member within an open end of said can body. 75
3. In a machine for making cans of the character described, the combination of means for rotating can bodies and separate collar members in axial alignment, and reciprocating tapered and shouldered chucks rotatable in unison with said last-mentioned means for assembling said member with the can bodies. 80
4. In a machine for making cans of the character described, the combination of means for rotating a can body and collar member in axial alignment, means for rounding up the can body during the rotation thereof, and a tapered and shouldered chuck for inserting said collar member within the rounded body. 85
5. In a machine for making cans of the character described, the combination of a rotating turret provided with pockets adapted to receive a can body, another turret cooperating with said pockets for rounding up the body during rotation of the turret, means for arranging a separate collar member in axial alignment with said body, and a tapered and shouldered chuck for truing the collar member, and automatically inserting said member within an open end of said body. 90
6. In a machine for making cans of the character described, the combination of a rotating turret provided with pockets adapted to receive a can body, means cooperating with said pockets for rounding up the body during rotation of the turret, a second turret adapted to receive a separate collar member and to rotate the same in axial alignment with said body, and means for automatically entering within and truing the collar member and inserting said member within an open end of said body. 95
7. In a machine for making cans of the character described, the combination of means for arranging a can body and separate collar member in axial alignment, means providing a backing for the can, and a tapered and shouldered chuck for automatically inserting said member within an open end of the can body. 100
8. In a machine for making cans of the character described, the combination of means for arranging a can body and separate collar member in axial alignment, means providing a backing for the can, and means for automatically entering within and truing and inserting said collar member within an open end of the can body, said backing means being adjustable to accommodate cans of different height. 105
9. In a machine for making cans of the character described, the combination of a rotating shaft, means on said shaft for carrying a can body and separate collar member arranged in axial alignment, means also carried on said shaft for inserting said member within an open end of said body, and a cam mounted concentrically with said shaft for operating said last-mentioned means. 110
10. In a machine for making cans of the character described, the combination of assembling mechanism, and means for arranging can bodies and separate collar members within the sphere of action of said mechanism, said mechanism including means projectable into an open end of the can body and having devices to true and position a collar member at a predetermined distance within said body. 115
11. In a machine for inserting collars into can bodies, the combination of a turret having pockets for receiving can bodies and conveying them from a receiving station to an assembling station, a turret having pockets for receiving and conveying collars to said assembling station and into alignment with the can bodies, rotary means having pockets cooperating with those of the can body conveying turret to confine and true-up the can bodies at the assembling station, and means truing-up the collars and causing them to be assembled within the can bodies. 120
12. In a machine for inserting collars into can bodies, the combination of a turret having pockets for receiving can bodies and conveying them from a receiving station to an assembling station, a turret having pockets for receiving and conveying collars to said assembling station and into alignment with the can bodies, rotary means having pockets cooperating with those of the can body con- 125
13. In a machine for inserting collars into can bodies, the combination of a turret having pockets for receiving can bodies and conveying them from a receiving station to an assembling station, a turret having pockets for receiving and conveying collars to said assembling station and into alignment with the can bodies, rotary means having pockets cooperating with those of the can body con- 130

veying turret to confine and true-up the can bodies at the assembling station and means entering within the collars and the can bodies and truing up the collars internally and causing them to be assembled within the can bodies.

13. In a machine for making cans of the character described, the combination of means for holding the can body and collar in line with each other, a chuck having a part to enter the collar and a shoulder to engage the outer edge of the collar and a part beyond said shoulder to fit within the can body, and means for actuating said chuck to insert the collar to a suitable distance within the can body.

14. In a machine for making cans of the character described, the combination of means for arranging a can body and a separate collar member in axial alignment, a backing for said can body, a part adapted to engage the peripheral edge of the collar to force it into the can body, and means entering within the collar for bringing the collar to the shape of the open end of the can body whereby to permit the part engaging the collar edge to move the collar into the body.

15. In a machine for making cans of the character described, the combination of means arranging two thin sheet metal cylinders in axial alignment, a backer for one said cylinder, and a reciprocating part having a shoulder for engaging the edge or cylindrical end of the other cylinder and entering within the latter to force the two cylinders to telescope with the inner cylinder located wholly within the outer.

16. In a machine for making cans of the character described, the combination of means having an annular collar propelling shoulder for arranging a flanged can body and collar member in axial alignment and means for automatically inserting said member into the flanged end of the can to a point substantially below the top of the can.

17. In a machine for making cans of the character described, the combination of means having an annular collar propelling shoulder for arranging a flanged can body and a collar member in axial alignment, means for truing the can body, means for inserting a collar member into the flanged end of the can to a point substantially below the top of the can.

18. In a machine for making cans of the character described, the combination of means for arranging a flanged can body and a collar member in axial alignment, means for engaging the edge of the collar and inserting it within a can body to a point substantially below the top edge of the can, said collar inserting means having a shape and dimension whereby it may enter within said can body and within said collar.

19. In a machine for making cans of the

character described, the combination of means for rotating a can body and collar member in axial alignment, means having an annular collar propelling shoulder for automatically inserting said member into the flanged end of the can to a point substantially below the top of the can.

20. A machine for making cans of the character described, comprising a turret having annularly spaced holders for tubular bodies and collars alined therewith, means for feeding bodies and collars to the successive holders, the turret also including socket members, collar plungers having parts entering within the collars and collar-propelling shoulders, and means acting in regular succession during continuous rotation of the turret to advance the socket members, move them to engage the bodies, advance the plungers to insert the collars in the respective bodies, and retract the plungers.

21. A machine for making cans of the character described, comprising a turret having annularly spaced holders for tubular bodies and collars alined therewith, means for feeding bodies and collars to the successive holders, the turret also including socket members, collar plungers having parts entering within the collars and collar-propelling shoulders, and means acting in regular succession during continuous rotation of the turret to advance the socket members, move them to engage the bodies, advance the plungers to insert the collars in the respective bodies, and retract the plungers, and mechanism arranged to receive the collared bodies and including means for clinching the collars therein.

22. A machine for making cans of the character described, comprising a turret having annularly spaced holders for tubular bodies and collars alined therewith, means for feeding bodies and collars to the successive holders, the turret also including socket members, collar plungers having parts entering within the collars and collar-propelling shoulders, means acting in regular succession during continuous rotation of the turret to advance the socket members, move them to engage the bodies, advance the plungers to insert the collars in the respective bodies, and retract the plungers, and means for positively discharging the bodies.

JOHN F. PETERS.
